(57) **CLAIM**

I claim the ornamental design for a clamshell style connector, as shown and described.

DESCRIPTION

FIG. 1 shows a first perspective view of the clamshell style connector;

FIG. 2 shows a first view of the clamshell style connector;

FIG. 3 shows a second view of the clamshell style connector from the opposite side as the first view;

FIG. 4 shows a first side view of the clamshell style connector;

FIG. 5 shows a second side view of the clamshell style connector;

FIG. 6 shows a top view of the clamshell style connector; and,

FIG. 7 shows a bottom view of the clamshell style connector. The broken line portion of the figure drawings is included to show portions of the article that form no part of the claimed design.
